UNITED STATES PATENT OFFICE.

JOHN E. BLAINE, JR., OF CINCINNATI, OHIO.

NAP-RESTORING DEVICE.

Application filed December 19, 1924. Serial No. 757,023.

This invention relates to improvements in devices for restoring nap to cloth, the device herein being particularly adapted for domestic use.

5 An object is to provide a device in which perfect control of the cloth-engaging portions of the nap-producing or raising element can be obtained, and by which the working edge of this element can be brought 10 toward, into or away from the cloth in micrometric degree, enabling the operator to produce nap of exactly the desired length or texture and, thus to accurately control the nap restoring operation.

15 Another object is to provide a nap restoring element, as a blade, which can be attached to an ordinary commercial type of safety razor handle or like mount, in lieu and manner of a razor blade, so that the 20 mount acts as a movable rest or support to be drawn along the goods during the re-napping operation, and as a fulcrum about which the mount may be rocked for bringing the working edge of the nap restoring 25 element toward, into or away from the goods.

Another object is to provide a mounting for the blade, which has a rounded working edge, and in which the nap restoring element, when attached to the plate, is slightly spaced away from the rounded working fulcrum edge or bears a tangent relation to the edge, and is therefore spaced outwardly therefrom.

35 A more specific object of the invention is to provide a reversible razor-like blade which may be attached to a razor handle of a commercial type, the blade having along each of two parallel sides a straight row of 40 nap raising or producing teeth each of different fineness, whereby either edge of the blade may be used and the blade substituted for the ordinary razor blade to act as a cloth surface refinishing tool, controlled and 45 manipulated by the mounting and handle.

Another object is to provide a device for the above purpose which may be cheaply manufactured either providing a blade for attachment to a safety razor of the ordinary type, or as a combination blade and holder

constructed in accordance with the teachings of this invention.

Other objects and certain advantages will be disclosed in the description of the drawing forming part of this specification, in 55 which:

Figure 1 is a side view of the device partly in section, shown in working position, and illustrating the manner of attachment of the blade to a safety razor handle 60 of a commercial type.

Figure 2 is a face view of the blade.

Figure 3 is a cross section of the blade on line 3—3 of Figure 2.

Figure 4 is a vertical longitudinal section 65 of the assembled device on line 4—4 of Figure 1.

The device comprises a curved plate 1, having a convex face 2, and also a concave face from which extends a handle 3. The 70 plate is substantially rectangular, and its two longer parallel edges are provided with inwardly extending teeth or prongs 5. My improved blade is attached upon and against the convex face 2, is also rectangular, and is of slightly less width than that 75 of the convex face between the longitudinal rounded fulcrum edges 4. The blade has two rows of knife edge teeth 8, 9, each of different fineness or spacing, and when the 80 blade is attached, the tips of the teeth lie parallel with respective or corresponding fulcrum edges 4, with the teeth tangentially related to the rounded edges 4, and preferably spaced inwardly therefrom as shown 85 in Figure 1. The relative sizes of plate and blade are such that when the blade is attached flatly against the concave face, the rows of teeth assume the tangent relation, thus causing the working points of the teeth 90 to be slightly spaced away from the working edge. The teeth are, however, preferably beveled as at 10 in the manner of the edges of a safety razor blade, and the blade herein has generally the form of that type 95 of blade, except, for the toothed edges. The blade is secured upon the plate preferably by a concavo-convex retainer 11, which has centrally of its concave side, a threaded 100 stem 12 passing through openings 17, 18, in

blade and plate and engaged with corresponding threads of the handle 3, so that when the parts are assembled, and the handle screwed to position, the retainer is drawn against the blade and said blade is flexed and securely held. The extent of clamping action may be varied to flex the blade in the desired degree and therefore correspondingly vary the degree of tangency relative to the convex face or rounded fulcrum edge. The retainer also has two projecting pins 13, spaced equidistantly at each side of the stem 12, and these pins traverse corresponding openings 14, 15, in plate and blade.

Any convenient means of fastening the blade may be used as well as other forms of fulcrum plate and handles for operating the same, the important feature being the relative disposition of the fulcrum edge of the plate and the toothed edge or edges of the blade, whereby adjustment of the plate about its fulcrum edge or side varies the extent of engagement between the teeth and cloth.

The blade may be attached in any preferred manner so that the above relation between the fulcrum plate and the blade is obtained, and the plates may be sold singly or in sets, either with or without holders and modified in shape to conform to other types of safety razor holders or handles.

Having described my invention, I claim:

1. In a device of the class described, a plate having a straight edge, and a blade having a straight row of teeth along one edge, said blade attached to said plate with its teeth in parallel relation to said straight edge, adjacent said edge, and spaced outwardly therefrom.

2. A blade for napping cloth adapted for attachment to a safety razor holder, having rows of teeth along opposite parallel sides in lieu of razor edges.

3. A blade for napping cloth, adapted to be attached to a safety razor holder, said blade having a straight row of nap-engaging teeth along one edge.

4. A flexible blade for napping cloth adapted for attachment to a safety razor holder, said blade having straight rows of teeth on respective opposite parallel edges.

5. In a device of the class described, a plate having a straight edge, and a blade having a straight row of teeth along one of said edges, said blade attached to said plate with its straight row of teeth adjacent the straight edge of the plate and spaced outwardly from the face of the plate.

6. In a device of the class described, a plate having a straight rounded edge and a blade having a straight row of teeth along one edge, said blade attached to said plate with the row of teeth overlying the curved edge of the plate tangent thereto.

7. In a device of the class described, a plate having a straight rounded edge and a blade having two parallel straight edges and teeth along said edges with one row of teeth overlying the rounded edge of the plate 70 tangent thereto.

8. A plate having a straight edge and a blade having a straight row of teeth, said blade attached to said plate with a row of teeth adjacent and parallel with said straight edge and spaced outwardly therefrom.

9. In a device of the class described, a plate having a straight rounded edge, and a blade having a straight row of beveled teeth, said plate flatly attached to said plate with a row of teeth adjacent and parallel with said straight edge with the beveled sides of the teeth facing and overlying the rounded straight edge of said plate, and handle means attached to the plate for rocking the same about its straight edge.

10. In a device for raising nap upon fabric, a plate having a convex side and a straight edge, a blade attached against said concave side tangentially thereto, said blade having a straight row of teeth disposed in parallel relation to the straight edge of the plate and spaced inwardly from the edge and outwardly from the convex surface, 95 whereby when the plate is rocked about its straight edge as a fulcrum the teeth are adjusted toward or away from the fabric.

11. In a device for restoring the nap of fabric, a curved plate of substantially rectangular configuration providing opposite parallel rounded edges as fulcrums for rocking the plate when one of the edges is engaged with the fabric, a blade attached to the convex side of the plate, said blade having straight rows of teeth parallel with, overlying and tangent to the rounded edges of the plate.

12. A flexible blade of substantially the dimensions of a safety razor blade, including spaced openings for attaching the blade, said blade having straight rows of beveled teeth in lieu of razor edges, whereby the blade can be attached to the razor mounting or holder and manipulated for a nap restoring operation by placing one straight edge of the mounting against the goods as a fulcrum and rocking the device in varying degree to vary the engagement of the teeth with the goods.

13. In a device of the class described, a plate having a straight working edge adapted to rest upon the goods and to act as a fulcrum, a blade attached flatly against the plate, said blade having a straight row of beveled teeth at one edge and spaced inwardly from said edge and outwardly from the face of the plate, whereby when rocking the plate about the working edge the degree of engagement of the teeth with the goods 130

can be varied and controlled while drawing the plate across the goods.

14. In a device of the class described, a plate having a straight edge rounded throughout its length, a blade attached to one face of said plate having a straight row of teeth along one edge, the tips of the teeth lying tangent to the rounded portion of the

straight edge, and spaced outwardly from the rounded surface, and means for rocking the plate about its rounded straight edge as a fulcrum to adjust the teeth toward, into or away from a fabric. 10

In witness whereof, I hereunto subscribe my name.

JOHN E. BLAINE, JR.
